UNITED STATES PATENT OFFICE

ANTHONY KOLAR, OF NEW YORK, N. Y.

DESIGN FOR AN ASH RECEPTACLE

Application filed February 26, 1930. Serial No. 34,655. Term of patent 3½ years.

To all whom it may concern:

Be it known that I, ANTHONY KOLAR, a citizen of Czechoslovakia, residing at New York, in the county of New York and State of New York, have invented a new, original, and ornamental Design for an Ash Receptacle, of which the following is a specification, reference being had to the accompanying drawing, forming part thereof.

The figure is a perspective view of an ash receptacle, showing my new design.

I claim:

The ornamental design for an ash receptacle, as shown.

In testimony whereof I have affixed my signature.

ANTHONY KOLAR.
